CLAIM

The ornamental design for a craft tray, as shown and described.

DESCRIPTION

FIG. 1 is a front, right, top perspective view of a craft tray, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right, top perspective view of the craft tray in a detached state; and,

FIG. 10 is an enlarged view of detail 10 in FIG. 1.

The dashed broken lines in the figures are for the purposes of illustrating portions of the craft tray that form no part of the claimed design.

The dash-dot-dash broken lines are for notating enlarged views and form no part of the claimed design.
